Japanese Design D1571646, Cutting for X-Wye Plotter, Published Mar. 13, 2017, JPO (Year: 2017).*

(Continued)

Primary Examiner — Nathaniel D. Buckner(74) *Attorney, Agent, or Firm* — Robert P. Michal, Esq.;
Carter, DeLuca & Farrell LLP(57) **CLAIM**

The ornamental design for a X-Y plotter for cutting, as shown and described.

DESCRIPTION

FIG. 1 is a front view of a cutting plotter showing our new design;

FIG. 2 is a rear view thereof;

FIG. 3 is a top plan view thereof;

FIG. 4 is a bottom plan view thereof;

FIG. 5 is a right side view thereof; and,

FIG. 6 is a left side view thereof.

The broken lines in the figures depict portions of the article which form no part of the claimed design.
